(57) **CLAIM**

The ornamental design for a fixing device for helmets, as shown and described.

DESCRIPTION

FIG. 1 is a perspective view of a fixing device for helmets, showing the new ornamental design;

FIG. 2 is a front view of the fixing device of FIG. 1;

FIG. 3 is a back view of the fixing device of FIG. 1;

FIG. 4 is a left side view of the fixing device of FIG. 1;

FIG. 5 is a right side view of the fixing device of FIG. 1; and,

FIG. 6 is a top view of the fixing device of FIG. 1.

The broken lines in the drawings depicting the shell of a helmet represent environmental subject matter that forms no part of the claimed design.

1 Claim, 6 Drawing Sheets
